VENDING MACHINE FOR FROZEN CONFECTIONS AND VENDING BELT THEREFOR

James Wellford Martin, Yonkers, N. Y.

Application July 30, 1937, Serial No. 156,472

4 Claims. (CL 62—91.5)

The present invention relates to the art of dispensing unitary packages of merchandise, and, more particularly, to a novel and improved vending machine and vending belt for dispensing frozen confections.

It is an object of the present invention to provide a vending machine particularly adapted to dispense unitary quantities or packages of frozen confections which eliminates the disadvantages 10 and inconveniences of conventional vending machines.

It is another object of the present invention to provide a vending machine including a vending belt bearing a plurality of vending packets 15 and adapted to be displaced step by step to make a single vending packet accessible to the consumer for each displacement.

It is a further object of the invention to provide an improved vending machine comprising 20 a heat-insulated cabinet adapted to be refrigerated by means of a suitable refrigerant and which may be filled with unitary packages of frozen confections equidistantly mounted on a vending belt.

25 The invention also contemplates a novel type of unit for merchandising and selling candy, frozen confections, such as ice cream, and the like in uniform packages mounted equidistantly along the length of a vending belt which 30 may be quickly and easily inserted as a unit into a vending machine for subsequently dispensing the packages in succession.

It is also within contemplation of the invention to provide a vending machine particularly for 35 frozen confections which is simple in construction, satisfactory and fool-proof in operation and which may be manufactured and sold on a commercial scale at a low price.

Other and further objects and advantages of 40 the invention will become apparent from the following description taken in conjunction with the accompanying drawings, in which;

Fig. 1 illustrates a vertical sectional view of a vending machine embodying the principles of the 45 present invention;

Fig. 2 depicts a sectional view taken on line 2—2 of Fig. 1;

Fig. 3 shows a horizontal sectional view having parts in elevation taken on line 3—3 of 50 Fig. 1;

Fig. 4 is a top elevational view of the vending machine shown in Fig. 1;

Fig. 5 illustrates a side view, somewhat fragmentary, of a portion of a vending belt;

Fig. 6 depicts a top elevational view of a

portion of the vending belt with a pair of unitary packages mounted thereon; and

Fig. 7 shows a vertical sectional view of a modified embodiment of the present invention into a vending machine.

Broadly stated, according to the principles of the present invention I provide a vending belt constituted of a strip of flexible cardboard, canvas or some other web of material having some flexibility and strength. On this belt I equidistantly mount a plurality of units of merchandise, such as unitary packages of candy, ice cream, or the like. I prefer to provide these unitary packages in the form of substantially cylindrical or tubular units which are secured to the vending belt proper by means of suitable fastening means, such as an adhesive, a glue, a cementitious material, paraffine, etc. I have found that a simple and inexpensive way of securely and removably fastening a large number of such unitary packages to the vending belt is to provide an auxiliary or supporting strip of paper or other similar sheet-like material which is placed above the units of cylindrical or other shape and is connected to the vending belt proper by means of staples, adhesives and the like at the points in between the unitary packages. The strength of the supporting strip is preferably such that it will securely support the unitary packages of merchandise but at the same time it can be readily torn away by the consumer to remove the unitary package or cartridge of merchandise from the vending belt.

The vending belt with the equidistantly distributed unitary packages of merchandise may 35 be formed in the form of an endless belt or in the form of a belt having two ends, as this will be more fully explained hereinafter. Clearly, the vending belt connects a large number of unitary packages of merchandise secured to the same 40 belt to form a single commercial unit which can be inserted by a simple and single operation into a vending cabinet or machine. This is of especial importance for the handling and dispensing of frozen confections which cannot be handled or 45 kept in unrefrigerated compartments for any length of time without deterioration and melting.

For dispensing the unitary packages of merchandise, I provide a cabinet or box. In the event that the merchandise is ice cream, or some 50 other frozen confection, this cabinet is carefully heat-insulated and is refrigerated by means of a suitable refrigerant, such as water ice, or dry ice. Within this cabinet I provide supporting means for a suitable length of vending belt which 55

is arranged on a system of rollers in order to permit easy displacement thereof, or is contained within the cabinet in a folded condition similar to the cartridge belts of machine guns. I also provide driving means for this vending belt engaging suitable depressions or perforations in the marginal portions of the belt, said driving means being normally inoperative and being capable of actuation to step by step displace the vending belt by the distance between the individual vending units. The driving means are preferably actuated by means of a coin-released actuating mechanism which will move the belt by a sufficient distance to move a new unitary package before a window where it becomes accessible to the operator and may be removed either by sliding it out sidewise from underneath the supporting strip or preferably simply by tearing the supporting strip open.

The invention will now be more fully described to those skilled in the art, reference being had to the accompanying drawings, in which:

Referring now more particularly to Figs. 1 to 4, a preferred embodiment of the present invention is illustrated. Reference character 1 denotes a cabinet or casing constituted of a heat insulating material. Openings 2 and 3 are provided in the top surface of the cabinet and are closed by means of covers 4 and 5. Removal of covers 4 and 5 makes the interior of the cabinet readily accessible for the insertion of merchandise in the form of vending belts and for a refrigerant, such as water ice or dry ice. Within the cabinet, I provide an endless belt 6 constituted of strong canvas, cardboard or some other sheet-like material having strength and which is flexible. A plurality of unitary packages of ice cream or some other similar merchandise and having a substantially cylindrical shape is denoted by reference character 7 and are secured equidistantly to the vending belt. The construction of the vending belt and the manner in which the packages are secured thereto will be best observed from Figs. 5 and 6. It will be noted that the cylindrical and unitary packages 7 of the ice cream are held by means of a supporting strip of cardboard or other readily severable material, 8, in position which strip is secured to the vending belt 6 properly by means of staples 9 or some other similar fastening means. As it clearly appears from Fig. 6, the supporting strip is inferior in width to that of the vending belt and is preferably slightly less in width than the package of ice cream in order to permit ready removal of the package. Perforations 10 are provided on the marginal edges of vending belt 6 which can be engaged by means of a sprocket wheel or some other driving means for propelling the belt during the dispensing operation.

The vending belt with the equidistantly distributed packages is provided in the form of an endless belt and is mounted on pulleys 11 and 12 in order to permit easy displacement thereof. Preferably, the lower pulleys 12 are constituted of two metal discs rotatably mounted in parallel spaced relationship on a shaft 13. These discs have such width that they only engage the marginal portions of the bending belt, whereas the packages of merchandise themselves may pass in between the discs, as this is indicated in dotted lines in Fig. 1. As it will be observed from Fig. 1, the endless vending belt is conducted in a zig-zag line between the pulleys in order to permit the storage of a substantial length of the belt and thus a large number of packages in the vend-

ing machine. The driving means comprise a sprocket wheel 14 adapted to engage the perforations in the marginal portions of the belt. Shaft 15 of sprocket wheel 14 is capable of being rotated by means of a conventional weight 16 suspended on a string 17 wound around the shaft. In the upper portion of the cabinet, a discharge opening 18 is provided and the vending belt is carried around a pin or small pulley 19 within easy access of the operator. To prevent access to the interior of the machine, a small hinged door or lid 20 is provided at one side of this discharge opening which permits the belt and the merchandise to pass but which prevents interference with the operation of the machine, or the removal of more than one piece or unit of the merchandise from the discharge opening at a time. I also provide a coin-actuated releasing mechanism for the driving means which will move the vending belt by a unitary distance for the insertion of a coin. In view of the fact that this type of coin-actuated release mechanism is well known in the art and does not form an object of the present invention, it has been shown only diagrammatically and has been denoted by the reference character 21. Within the cabinet a piece or cake of solid refrigerant, preferably dry ice 22 is placed on a shelf 23 which provides the refrigerating temperature necessary for preserving ice cream or other frozen confections in a wholesome and satisfactory condition. A partition 24 is provided for confining the refrigerating gases produced by the evaporation of the dry ice and to provide a good and efficient cooling of the vending belt and of the frozen confections thereon.

From the foregoing description, the operation of my novel vending machine and vending belt will be readily understood by those skilled in the art. The vending belt with the unitary packages of ice cream mounted thereon is preferably delivered as a single unit which can be conveniently and easily handled and may be inserted in the cabinet and placed around the pulleys 11 and 12 through the opening 2 after cover 4 has been removed. A cake of dry ice 22 is placed on shelf 23 through opening 3. When a coin is inserted into coin drop 21, this will actuate the releasing mechanism (not shown) for the driving means and will cause the vending belt and the packages 7 thereon to be displaced by sprocket wheel 14 and weight 16 by a distance corresponding to the distance between the successive packages. This will cause one of the packages to lift up lid 20 and to appear in the discharge opening 18 of the cabinet where the operator may tear off the supporting strip and may remove the package of ice cream. After all of the packages have been sold and removed, the remaining vending belt may be removed and may be exchanged with a new one or may be replenished with new packages of ice cream. Of course, those skilled in the art will readily understand that the vending belt may be constituted of a cheap material such as cardboard which may be thrown away after it has been used or may be made of a stronger and more expensive material such as canvas and the like which may be reshipped to the factory to be filled with new units of confections. Likewise, the filling may be effected directly in the vending machine, with individual units of ice cream, without removing the vending belt from the pulleys.

The modified embodiment of the invention illustrated in Fig. 7 is in many respects similar

to the vending cabinet described in the foregoing. Essentially, a cabinet or casing 31 is provided constituted of a heat insulating material. Preferably, the cabinet is built of two sheets of metal 32 and 33 having a suitable heat insulating material or mass 34 disposed in between. Within the main compartment 35 of this cabinet, I provide a vending belt 36 carrying equidistantly mounted unitary packages 37 thereon by means 10 of a supporting strip or strips 38. It will be readily observed from the drawing that the vending belt is folded zig-zag like in the cabinet to be able to store a substantial quantity of merchandise in a single cabinet. The individual layers 15 of the vending belt are separated from each other by means of sheets or strips of cardboard 39 which prevent the individual layers from freezing together and thus to interfere with the correct operation of the machine. Above the main compartment of the vending cabinet there is a cake 20 of dry ice 40 or some other refrigerant located which maintains the cabinet and its contents at the desired low temperature.

The discharging mechanism comprises a sprocket wheel 41 constituted of two discs mounted at a distance from each other to permit the passage of the ice cream packages therebetween and which cooperates with a pressure roller 42. Hereafter, the vending belt is passed in a sharply reversed direction over an edge 43 and is led underneath an idler 44 to sprocket wheel 45. Sprocket wheel 45 is actuated by means of a weight 46 suspended from a string 47 wound around shaft 48 of the sprocket wheel. A small 30 window or discharge opening 49 is provided above the edge 43 through which one of the packages becomes accessible to the operator, while a spring-held lid 50 prevents access to the interior of the cabinet and unauthorized removal of merchandise. Preferably, a coin-actuated release mechanism (not shown) is provided for the control of the driving means and to propel the vending belt by a unitary distance for the insertion of each coin into a conventional slot 51. The vending belt 52 from which the packages of ice cream have been removed accumulates in the right hand compartment 53 from which it may be removed at convenient intervals through door 54. Of course, the vending belt may be 40 constituted of any suitable material, for example, canvas, or cardboard. Generally speaking, cardboard of suitable thickness and strength is preferred since this is inexpensive enough for to be thrown away after a single use. In view 55 of the similarity of construction, the operation of this modified embodiment of my vending machine will be readily understood by those skilled in the art without any further explanation. Same as in the embodiment illustrated in Figs. 1 to 6, it is preferred to supply the bending belt with the mounted packages of merchandise as a unit which may be quickly inserted into the machine and may be quickly replaced with a new one after the old one has been consumed.

60 It will be noted that the vending machines embodying the principles of the present invention provide a number of important advantages. First of all, a simple, inexpensive and fool-proof vending machine is provided which may be manufactured, sold and operated with a minimum of servicing or trouble.

65 It is also to be observed that the present invention successfully solves the problem of automatically merchandising ice cream and other frozen confections which could not be conven-

iently handled by prior vending machines. The vending machine and vending belt embodying the principles of the present invention permits to deliver a large number of ice cream packages as a single unit in the form of a belt which may be conveniently handled and which may be inserted into the machine at a moment's notice. Of course, this circumstance is of great practical importance in view of the fact that ice cream will quickly deteriorate and melt if exposed for 10 any length of time to room temperatures during the procedure of insertion, as this was the case in prior ice cream vending devices.

Moreover, the present invention provides a new article of manufacture, a vending belt supporting equidistantly mounted frozen confections or some other type of merchandise thereon which may be readily manufactured and sold on a practical and commercial scale and which provides a fundamentally new and advantageous 20 way of merchandising and delivering confections of the described type.

Although the present invention has been described in connection with a few preferred embodiments thereof, variations and modifications 25 may be resorted to by those skilled in the art without departing from the principles of the present invention. I consider all of these variations and modifications as within the true spirit and scope of the present invention as disclosed in 30 the present description and defined by the appended claims.

I claim:

1. In a vending machine having means for spacedly supporting a plurality of packages of frozen confections, and having dispensing means for displacing said packages toward a discharge opening to expose to the exterior a single package at a time; refrigerating means for said machine, said refrigerating means comprising in combination a heat-insulated casing having substantially gas-tight bottom and side walls, a dry ice holding device in said casing adapted to hold dry ice for filling said casing with cold and dry gases and for maintaining a low temperature therein, and a permanently open discharge opening in the top portion of said casing through which gases produced by said dry ice continuously overflow and block the entrance of outer warm and moist air into the casing; said refrigerating means being adapted to cooperate with said dispensing means to surround them and the packages of frozen confections with an atmosphere considerably below its dew point whereby sticking and refreezing of said packages to the dispensing means is positively prevented.

2. In a vending machine having a vending belt for holding a plurality of packages of frozen confections severally mounted thereon at regular spaced intervals to prevent direct contact and freezing together thereof, perforations in said belt, and dispensing means including a sprocket wheel engaging said perforations, and driving means for said sprocket wheel adapted to displace said belt towards a discharge opening and to successively expose the packages thereon to the exterior for the removal of a single package at a time; refrigerating means for said machine, said refrigerating means comprising in combination a heat-insulated casing having substantially gas-tight bottom and side walls for said vending belt and said driving means, a dry ice holding device in said casing adapted to hold dry ice for filling said casing with cold and dry gases and for maintaining a low temperature therein, and

- 5 a permanently open discharge opening in the top portion of said casing through which gases produced by said dry ice continuously overflow and block the entrance of outer warm and moist air into the casing; said refrigerating means being adapted to cooperate with said dispensing means to surround them and the packages of frozen confections with an atmosphere considerably below its dew point whereby sticking and refreezing of said packages to the dispensing means is positively prevented.
- 10 3. In a vending machine having an endless belt for holding a plurality of packages of frozen confections severally mounted thereon at regular spaced intervals to prevent direct contact and freezing together thereof, perforations in the marginal portions of said belt, and dispensing means including guiding means for said belt, a sprocket wheel engaging said perforations in said belt, and driving means for said sprocket wheel adapted to displace said belt towards a discharge opening and to successively expose the packages thereon to the exterior for the removal of a single package at a time; refrigerating means for said machine, said refrigerating means comprising in combination a heat-insulated casing having substantially gas-tight bottom walls for said vending belt and said driving means, a dry ice holding device in said casing adapted to hold dry ice for filling said casing with cold and dry gases and for maintaining a low temperature therein, and a permanently open discharge opening in the top surface of said casing through which gases produced by said dry ice continuously overflow and block the entrance of outer warm and moist air into the casing; said refrigerating means being adapted to cooperate with said dispensing means to surround them and the packages of frozen con-

fections with an atmosphere considerably below its dew point whereby sticking and refreezing of said packages to the dispensing means is positively prevented.

- 15 4. In a vending machine having a vending belt for holding a plurality of packages of frozen confections severally mounted thereon at regular spaced intervals to prevent direct contact and freezing together thereof, said belt being folded in a zig-zag-like manner to provide a substantially rectangular unit, perforations in the marginal portions of said belt, and dispensing means including guiding means for said belt, a sprocket wheel engaging said perforations in said belt, and driving means for said sprocket wheel for displacing said belt towards a discharge opening and to successively expose said packages to the exterior through said discharge opening for the removal of a single package at a time; refrigerating means for said machine, said refrigerating means comprising in combination a heat-insulated casing having substantially gas-tight bottom walls for said vending belt and said driving means, a dry ice holding device in said casing adapted to hold dry ice for filling said casing with cold and dry gases and for maintaining a low temperature therein, and a permanently open discharge opening in the top surface of said casing through which gases produced by said dry ice continuously overflow and block the entrance of outer warm and moist air into the casing; said refrigerating means being adapted to cooperate with said dispensing means to surround them and the packages of frozen confections with an atmosphere considerably below its dew point whereby sticking and refreezing of said packages to the dispensing means is positively prevented.

JAMES WELLFORD MARTIN.
